Primary Examiner — Samantha Q Lawrence*Assistant Examiner* — Holly M Rodriguez(74) *Attorney, Agent, or Firm* — Fish IP Law, LLP(57) **CLAIM**

The ornamental design for a TV mount bracket, as shown and described.

DESCRIPTION

FIG. 1 is a front perspective view of a TV mount bracket showing my new design.

FIG. 2 is a front view thereof.

FIG. 3 is a rear view thereof.

FIG. 4 is a left side view thereof.

FIG. 5 is a right side view thereof.

FIG. 6 is a top side view thereof.

FIG. 7 is a bottom side view thereof.

FIG. 8 is a front perspective view in an alternate position of use.

FIG. 9 is a rear perspective view thereof; and,

FIG. 10 is a front perspective view in another alternate position of use.

The broken lines in figures show portions of the TV mount bracket that form no part of the claimed design.

1 Claim, 9 Drawing Sheets(56)
